UNITED STATES PATENT OFFICE

139,080

DESIGN FOR A CULTIVATOR

Abraham J. Grafman, Los Angeles, Calif., assignor to Van Tuyl Engineering Corporation, Los Angeles, Calif., a corporation of Michigan

Application July 25, 1944, Serial No. 114,549

Term of patent 14 years

(Cl. D39—1)

To all whom it may concern:

Abraham J. Grafman, a citizen of the United States and a resident of Los Angeles, in the county of Los Angeles, State of California, has invented a new, original, and ornamental Design for a Cultivator, of which the following is a specification, reference being had to the accompanying drawing, forming part thereof, and in which

Fig. 1 is a perspective view of the cultivator showing my new design; and

Fig. 2 is a front end view of the same.

I claim:

The ornamental design for a cultivator, as shown.

ABRAHAM J. GRAFMAN.
